UNITED STATES PATENT OFFICE.

HUGH T. REED, OF RICHMOND, INDIANA.

SHELVING.

SPECIFICATION forming part of Letters Patent No. 359,691, dated March 22, 1887.

Application filed October 9, 1886. Serial No. 215,778. (No model.)

To all whom it may concern:

Be it known that I, HUGH T. REED, a citizen of the United States, residing at Richmond, in the county of Wayne and State of Indiana, 5 have invented certain new and useful Improvements in Shelving; and I do hereby declare the following to be a full, clear, and exact description of the invention, such as will enable others skilled in the art to which it appertains to 10 make and use the same.

My invention consists of knockdown metallic shelving adapted for general purposes—such, for instance, as shown in a prior patent granted to me October 6, 1885, and in a prior 15 application made by me May 11, 1886.

One object of this invention is to provide an improved construction in means for sustaining the shelves against the posts, so that the parts may be easily joined in erecting the shelving 20 and quickly separated in taking it down.

Another object is to provide an improved method of conveying wires for general uses—such as for telephones, electric lights, &c.

The novel features of this invention are 25 specifically pointed out in the claims at the close of the specification, and the construction and combination of the different parts are set forth in the following description and annexed drawings.

30 The same letters of reference indicate identical parts in all of the figures.

Figure 1 is a perspective view of a section of two panels of the shelving. Fig. 2 illustrates the manner of attaching the screw-hook 35 B to the post A in the threaded apertures a. Fig. 3 indicates the manner of supporting the shelf C upon the screw-hook B. Figs. 4 and 7 are different views of a circular flange for ends of posts and for attachment to base or 40 ceiling, and Figs. 5 and 8 and 6 and 9 show modified forms of the same for use on posts next to wall and in corners. Fig. 10 illustrates an open metallic shelf, C, said shelf being curved at corners to fit against cylindrical 45 posts, and to be furnished, where required, with the rollers C². Said shelf is made in one piece, and consists of long and short ribs perpendicular to each other at regular or irregular intervals, one or more longitudinal ribs 50 to have a vertical thickness at the middle point thereof proportioned to the vertical thickness of the same ribs at either end thereof,

as five to three, more or less, as the length of shelf may require, and the said ribs to taper in vertical thickness from the middle point thereof 55 toward and to either end from the greater to the lesser dimension, as shown in Fig. 1, and all portions of the upper surface of the longitudinal ribs to be in the same plane, so as to give the maximum strength with the minimum 60 weight to each shelf. Fig. 11 is a cross-section of Fig. 10, showing the ribs C¹ and the roller C² of the shelf C. Fig. 12 illustrates a wooden shelf, C', a roller, C³, and suitably-formed ears D, attached to the said shelf, said 65 ears to be provided with openings d to fit on the screw-hooks B. Fig. 13 indicates the manner of connecting two open metallic shelves by a clamp, e, placed so as to embrace the two side ribs, c⁴ c⁴; and Fig. 13^a is a cross-section 70 showing its form and manner of attachment to ribs c⁴ c⁴. Fig. 14 indicates the manner of joining two posts A A by a brace, h, designed to support a rod in front of and near the top of the shelving, to which curtains may be attached, as indicated in Fig. 1. Fig. 15 shows an end elevation of shelving having three posts, with one post shorter than the other two, the object being to provide a ledge or counter. Fig. 16 indicates the manner of attaching an 80 annunciator, L, to a post, A, with wires l in a tubular post. Fig. 17 shows an electric bulb, M, attached to a post, A, having connecting-wires within the post.

My shelving is composed, in the main, of 85 corner-posts A, preferably tubular, screw-hooks B, and shelves C or C'. The posts are set in suitably-formed flanges E F G, to be fastened to or in the floor or other base, such as K. The posts are pierced with a vertical 90 series of threaded apertures, a a, placed at any desired interval, and the screw-hooks B are screwed into said apertures, and when in position receive the corners of a shelf fitting over the vertical portion and resting on the horizontal part thereof.

As indicated in Fig. 1, the posts A A may be connected by horizontal rods I as a support for curtains, or similar rods for curtains may be supported by the brace h. (Shown in Fig. 100 14.)

As shown in Figs. 10, 11, and 12, I have designed a shelf for packages or heavy books, having two or more rollers, C² or C³, near its

front edge, said rollers, when in place, to have their upper surface slightly above the upper surface of the shelf, and when so placed to revolve on their axes when weights of packages 5 or books are superimposed.

Fig. 15 illustrates a style of duplex shelving in which the top shelf of the lower portion thereof may be used as a counter.

I submit as a novelty in construction and 10 device the use of the tubular post with the connecting tubular rods, as shown in Figs. 1 and 14, for the conveyance of wires for annunciators and electric lighting, as indicated in Figs. 16 and 17. For the annunciator L or the 15 bulb M may be substituted a telephone-box, gas-burner, or faucet, and the tubular posts and rods may be used as speaking-tubes or to convey water, steam, and gas.

I claim as my invention—

20 1. In knockdown metallic shelving, the combination, with a suitable base, of vertical tubular supports or standards having screw-threaded openings at intervals along their surfaces and screw-threaded hooks for engagement therewith, said hooks serving as supports for 25 the skeletonized shelves, substantially as described.

2. In knockdown metallic shelving, the com-

bination of the tubular supports or standards for the same and their base-sockets secured to 30 a counter or base, and having electric conductors passing therethrough for signaling or illuminating purposes, substantially as described.

3. In knockdown metallic shelving, the skeletonized shelf composed of a series of longitudinal ribs having transverse ribs at intervals, said longitudinal ribs having a vertical thickness at their middle greater than at the ends thereof, whereby strength and lightness are attained, said shelf having rollers at the edges thereof to prevent friction in bodies moving thereon, substantially as described.

4. In knockdown metallic shelving, the combination, with the base or counter K, the tubular 45 standards or supports A, and their sockets secured thereto, and having the shelf-supporting hooks B, of the skeletonized centrally-strengthened shelf C, supported on said hooks B, and the rods I, extending along the top of 50 the standards or supports, substantially as described.

HUGH T. REED.
